UNITED STATES PATENT OFFICE.

EDWIN F. ENGLAND, OF NEW YORK, N. Y.

MEANS FOR AUTOMATICALLY STOPPING RAILROAD-MOTORS.

1,115,915.

Specification of Letters Patent.

Patented Nov. 3, 1914.

Application filed June 18, 1913. Serial No. 774,277.

To all whom it may concern:

Be it known that I, EDWIN F. ENGLAND, a citizen of the United States, and a resident of the borough of Bronx, city, county, and State of New York, have invented certain new and useful Means for Automatically Stopping Railroad-Motors, of which the following is a specification.

My invention relates to rail road motors, either steam or electric, in connection with which an emergency brake system is used, and the object is to effect automatically the application of the emergency brake, should the motor attempt to pass a signal properly set to indicate that the road ahead is not clear or available.

The invention consists primarily in emergency brake release mechanism on the motor adapted to be actuated by a trip lever on a semaphore or similar signaling device when the latter is set against further progress; and secondarily, in the specific construction and arrangement of parts described and claimed whereby the parts of the brake setting mechanism are sustained in their proper relative positions, and whereby undue jar or concussion is avoided when such mechanism is tripped by the signaling device, all as hereinafter set forth.

In the accompanying drawings, Figure 1, is a diagrammatic view illustrating the practical application of my invention; Fig. 2, a sectional elevation of my emergency brake release mechanism; Fig. 3, a detail view of the contact lever and its buffers; Fig. 4, a detail view of the release levers; and Fig. 5 a detail view of the detent.

It is to be understood that by the term motor as used herein I mean to designate locomotives, electric motors or any power driven motor traveling on tracks and equipped with an emergency brake of any kind, air, vacuum, electric or otherwise.

M represents symbolically a rail road motor of any kind, on which my emergency brake release mechanism is installed in any suitable manner, preferably by inclosing it in a box B on the motor body,—the only protruding parts being the outer end of the rock shaft S, the contact lever C, and the buffer C'.

The contact lever C, is rigidly secured to the outer end of the rock shaft S, which latter is mounted in suitable bearings b, b. The contact lever C, in its normal position is preferably inclined from the perpendicular

and hence tends to turn the shaft, but this tendency to gravitate is counteracted by the detent D which sustains the rock shaft S and contact lever in said normal position. The detent D may consist of a pawl d, and ratchet wheel d¹, of ordinary construction or of any other suitable mechanical expedient, that will admit of the turning of the shaft S in one direction while preventing its turning in the opposite direction. To limit the extent of motion in said opposite direction, and hence to limit the upward thrust of the contact lever C, the shaft S is provided with a pin or shoulder s, for contacting with a stop b¹, on a bearing b, or other stationary part. The shaft S and contact lever C, being thus held in one direction by the detent D, while free to turn in the opposite direction within a prescribed limit, it is desirable to counteract any tendency to looseness or vibration within this limit, so as to maintain the contact lever C steadily in its normal position unless or until operated positively by a trip lever T, connected with a semaphore T' or other signal device. For this reason I interpose a stiff coiled spring s¹, between one of the bearings b, and a collar s², on the shaft, and also provide the latter with another collar s³, which contacts with the other bearing b, as shown in Fig. 2, thereby reinforcing and holding the shaft S, and contact lever C, by augmented frictional contact, firmly against accidental displacement while allowing the shaft S and contact lever C, to yield and turn when the latter encounters a trip lever T.

The protruding end of the trip lever T is preferably made circular in cross section, and may even consist of a cylindrical roller if desired, so as to reduce frictional resistance and render engagement with the contact lever C, as smooth as possible; and in order to reduce the jar of initial contact between trip lever T and contact lever C, the latter may be formed with a buffer contact surface c, between which and the body of the lever C, are interposed a series of springs c¹, c², which receive and neutralize the brunt of impact. As a further means of mitigating the possible violence of encounter between the contact lever C, and trip lever T, should the motor be traveling at a high rate of speed, I provide a buffer C' to receive the extreme upward thrust of said contact lever C; and also connect the actuating arm or lever a, (rigidly secured to the rock shaft S)

to the emergency brake release lever F, by means of an elastic resilient spring e, which insures the gradual application of the brake and thus obviates the danger of instantaneous or sudden stoppage. Furthermore it may be noted in this connection that the steadyng spring s¹, also acts as a retarder or brake to counteract concussion and aid in gradually and gently transmitting to the emergency brake release arm E, the motion derived from the contact lever C, by reason of its engagement with and passage over a trip lever T. It is to be understood that the emergency brake release arm E, connects with, or is the means of actuating, any desired or known form of brake mechanism, either directly or indirectly as may be found most expedient.

By connecting the trip lever T with, and actuating it by means of, a semaphore or similar signal in such manner that the trip lever T is set for action when the signal is set for danger or block, I obviously and effectually guard against danger from carelessness, indifference or incapability on the part of the engineer or motor man, since so long as the signal is set at danger the motor cannot pass the signal without automatically applying the emergency brake. And by my construction and arrangement of parts this can be accomplished gradually and safely, obviating jar and concussion.

What I claim as my invention and desire to secure by Letters Patent is,

1. In combination with a motor and a rock shaft, a contact lever rigidly secured to the outer end of said rock shaft and normally inclined from a perpendicular, means sustaining the same in normal position, a trip lever for coöperation with said contact lever, and a spring on said shaft, an emergency brake release arm and a resilient connection between the same and said rock shaft.

2. In combination with a motor and a rock shaft, a contact lever rigidly secured to the outer end of said rock shaft and normally inclined from a perpendicular, means sustaining the same in normal position, a trip lever for coöperation with said contact lever, a spring on said shaft, an emergency brake release arm, a resilient connection between the same and said rock shaft, and a yielding buffer on said contact lever.

3. In combination with a motor and a rock shaft, a contact lever rigidly secured to the outer end of said rock shaft and nor-

mally inclined from a perpendicular, means sustaining the same in normal position, a trip lever for coöperation with said contact lever, a spring on said shaft, an emergency brake release arm, a resilient connection between the same and said rock shaft, a yielding buffer on said contact lever, and a second buffer to receive the extreme upward thrust of said contact lever.

4. The combination with a motor and a rock shaft, of an actuating arm, an emergency brake release arm, a spring connecting said arms, a contact lever rigidly connected with one end of said rock shaft, a spring coiled about the rock shaft with means for reinforcing and holding said shaft and contact lever, by augmented frictional contact, firmly against accidental displacement yet allowing the shaft and contact lever to yield and turn when the latter encounters a trip lever.

5. The combination with a motor and a rock shaft, of an actuating arm, an emergency brake release arm, a spring connecting said arms, a contact lever rigidly connected with one end of said rock shaft, a spring coiled about the rock shaft with means for reinforcing and holding said shaft and contact lever, by augmented frictional contact, firmly against accidental displacement yet allowing the shaft and contact lever to yield and turn when the latter encounters a trip lever, said contact lever normally inclined from the perpendicular, and means sustaining the rock shaft and contact lever in normal position.

6. The combination with a motor and a rock shaft, of an actuating arm, an emergency brake release arm, a spring connecting said arms, a contact lever rigidly connected with one end of the said rock shaft, a spring coiled about the rock shaft with means for reinforcing and holding said shaft and contact lever, by augmented frictional contact, firmly against accidental displacement yet allowing the shaft and contact lever to yield and turn when the latter encounters a trip lever, said contact lever normally inclined from the perpendicular, means sustaining the rock shaft and contact lever in normal position, and means for limiting the extent of motion in one direction and the upward thrust of said contact lever.
